Filed Jan. 23, 1961, Ser. No. 63,664

Term of patent 3½ years

(Cl. D34—5)

FIG. 1

FIG. 2

FIGURE 1 is a front perspective view of a tiddlywinks-type game board showing my new design; and

FIGURE 2 is a bottom plan view thereof.

The dominant portions of my design are shown in full lines on the drawing. The rear of the grandstand is plain and unornamented.

I claim:

The ornamental design for a tiddlywinks-type game board, substantially as shown and described.
